Patented Jan. 15, 1918.

UNITED STATES PATENT OFFICE.

HENRY S. LOUD, OF NEW YORK, N. Y.

PROCESS AND APPARATUS FOR IMPREGNATING WOOD AND OTHER POROUS MATERIALS WITH PRESERVATIVE LIQUID.

1,253,844.

Specification of Letters Patent. Patented Jan. 15, 1918.

Application filed February 9, 1916. Serial No. 77,337.

To all whom it may concern:

Be it known that I, HENRY S. LOUD, a citizen of the United States, residing in the borough of Manhattan, city, county, and State of New York, have invented new and useful Improvements in Process and Apparatus for Impregnating Wood and other Porous Materials with Preservative Liquid, of which the following is a specification.

10 My invention relates to improvements in processes and apparatus for impregnating wood and other porous materials with a preservative liquid, its object being to provide a process, and apparatus for carrying out such process, adapted to reduce to the minimum the gross amount of preservative liquid necessarily used, and also to economize in time, labor, and power employed; and consists generally in treating groups of materials successively in a three-fold cycle of retorts, whereby fluids and the stored power or energy in one retort is transferred to the next retort of the cycle, and in other improved steps and features hereinafter shown, 25 described and claimed.

The accompanying drawing forming part of this specification illustrates diagrammatically an apparatus suitable for carrying out my improved process. In said drawing 30 A, B, and C, respectively represent three similar retorts in which the groups of railway ties or other materials, are placed for treatment, and are then hermetically sealed. These retorts must be strong enough to withstand the maximum internal pressure required, as well as the crushing stress of the atmosphere when subjected to a vacuum. The pipes 1, 2, and 3, controlled respectively by valves 4, 5, and 6, connect the bottoms 35 of the respective retorts through the common pipe E with the suction end of the pump D, which pipe E leads to a source of preservative oil supply not shown, and is provided with a cut-off valve 7. The pump 40 D is preferably placed so that the liquid from any retort can flow into it by gravity. G is the discharge pipe from the pump D, and is connected with the several retorts by the pipes 8, 9, and 10, having cut-off valves 45 11, 12, and 13, respectively. The pipe G is also connected by the pipe 14, having a cut-off valve 15, with the oil supply pipe E

between its cut-off valve 7 and the source of supply. The pipes 16, 17, and 18, having cut-off valves 19, 20, and 21, lead respectively to the top of the retorts A, B, and C. Branch pipes 22, 23, and 24, having cut-off valves 26, 27, and 28, respectively, connect the pipes 16, 17, and 18, through the common pipe 25, provided with relief valve 37, 55 which is set to open at the maximum predetermined pressure to be attained in the retorts in carrying out the process as herein-after described, with nozzles 29, 30 and 31, respectively provided with cut-off valves 32, 33, and 34, and entering the open ends of the pipes 18, 17, and 16, inclosed in the manifold H. K is an air compressor connected by means of the pipe 35, having cut-off valve 36, with the pipe 25, and also through the 60 by-pass pipe 50 having a cut-off valve 51 with the pipe 25 on the other side of the valve 37. The bottoms of the retorts A, B, and C, are also connected through their outlet pipes 1, 2 and 3, and the branch pipes 75 38, 39, and 40 respectively, fitted with cut-off valves 41, 42, and 43, and the common pipes 44 and 45, with the manifold H. The pump D is also connected with the manifold H by means of the pipe G, branch pipe 46, 80 having cut-off valve 47, and pipes 44 and 45. The retorts are fitted with car tracks, heating coils, &c., in the usual manner for equipping plants of this character, and the pump and air compressor are supplied with steam, 85 etc., as is also customary.

The apparatus is adapted for use with any process in which compressed air, preservative under pressure, and vacuum, are employed to carry out the treatment of the 90 materials, but is especially designed and equipped for carrying out my improved process as hereinafter described.

My improved process and the method of operating the same may be described as follows: A group of the materials, for example, a train of cars loaded with railway ties, is placed in each of the retorts and the doors of the retorts then closed. The valves 7, 47, and 19, then being opened, the pump 100 D is started, drawing preservative oil from the source of supply and forcing it through pipes G, 46, 44, 45, manifold H, and pipe 16, to the retort A, the oil being discharged

in such manner as to thoroughly drench the ties. The amount of preservative thus conveyed into the retort should preferably be in excess of the net amount of preservative retained in the ties when the treatment is completed, and is indicated by means of a pet cock 48 near the bottom of the retort, through which the preservative accumulating in the retort will flow when it reaches the predetermined level. The valve 47 and pet cock 48 are then closed, and the valve 41 is opened permitting the flow of the preservative from the retort A into the manifold H. The valve 36 in pipe 35 and the valve 34 in nozzle 31, are then opened, and the compressor K started to force air through the pipes 35, 25, and nozzle 31, into the pipe 16, thereby carrying preservative from the manifold H through the pipe 16 and open valve 19 into the retort A, thus re-establishing the drenching operation under progressively increasing air pressure in the retort until the maximum pressure desired has been attained, the liquid circulating from the retort through the pipes 1, 38, 45, manifold H, and pipe 16, as long as the air flows from the compressor K. The air compressor is then cut off by closing the valve 36, the valves 34, and 19, also being closed.

In the meantime the ties on the train of cars in the retort B have been drenched with preservative in the same manner as the ties in the retort A were preliminarily drenched, the valves 7, 47, and 20, having been opened and the oil from the pump D flowing through the pipes G, 46, 44, 45, manifold H, pipe 17, into the top of the retort B, and the pump then cut off, as above described, by the closing of the valve 47. The valves in the pipes 8, 22, and nozzle 30, being then opened, oil is forced by the pump D through the pipes G and 8 into the retort A forcing out the air contained therein through the pipes 16, 22, 25, nozzle 30, pipe 17, carrying oil from the manifold H into the retort B and circulating the same through it as above described, the full pressure of the air being maintained in the retort A by the valve 37 being set to open at the maximum air pressure in the retort A. The flow of air from A to B continues the drenching operation already begun in B. When all of the air is expelled from the retort A, completing the drenching operation in B, and the ties in A are completely submerged by the preservative liquid, the valve 26 is closed preventing the outflow of the oil from the retort A, the continued operation of the pump D forcing additional preservative into the retort A until the maximum hydraulic pressure desired has been attained to secure the desired final impregnation of the ties. The valve 11 in the branch pipe 8 is then closed shutting off the further flow of oil from the pump D. Meanwhile the preliminary drenching of the

ties in the retort C has been completed by the forcing of the preservative by the pump D through the pipes G, 46, 44, 45, manifold H, and pipe 18.

The valve 4 in pipe 1, valve 12 in pipe 9, valve 27 in pipe 23, valve 32 in pipe 25, are then opened and the operation of the pump D serves to draw the accumulated surplus preservative from retort A through the pipes 1 and E, and discharge the same through G, 75 and 9, into the retort B to displace all of its contained air, which flows from the retort B through the pipes 17, 23, 25, relief valve 37, nozzle 29 and pipe 18 to the retort C carrying with it preservative for the continued drenching of the ties therein under increasing atmospheric pressure the preservative circulating from the retort C through the pipe 3, branch pipe 40, open valve 43, pipes 44 and 45 to the manifold 85 H. When the retort B has been completely filled with the preservative the valve 27 is closed, and additional preservative forced into the retort under increased pressure by the pump through the pipes G and 9, as 90 above described with reference to the retort A. The emptying of the retort A of oil, as above described, by means of the pump D, creates a vacuum in A which is maintained as long as is necessary, and then the valve 95 4 is closed and the vacuum in A is broken by opening the valve 49 to the atmosphere. The door of the retort is then opened, the treated ties are withdrawn, and another train of untreated ties introduced, and the 100 retort again closed and the ties preliminarily drenched with preservative, and the drenching continued by means of compressed air discharged from the retort C, as it is filled with preservative from the retort B.

When desired the fresh charges of ties in the several retorts may be subjected to a vacuum created by the pump D before they are drenched, in order to secure deeper initial penetration of the preservative when 110 air pressure is applied.

In case a modified process is desired to be carried out, omitting the drenching operation entirely, and merely subjecting the ties to compressed air, and preservative under 115 increased pressure, and then to a vacuum, the valves 4, 11, and 41 are closed and valves 51 and 26 are opened connecting the air compressor K through pipes 50, 25, 22, and 16, with the retort A, and K is operated 120 until the desired air pressure has been attained. Then the valves 51 and 26 are closed cutting off the compressor, and valve 11 opened and preservative is forced into the retort by means of the pump D through the 125 pipes G and 8, in the manner previously described, until the desired hydraulic pressure has been attained in retort A. The vacuum having been maintained in the retort A until the treatment of the ties therein is com- 130

pleted, air is admitted through the valve 49, the door of the retort opened, the treated charge removed, and a new charge introduced, after which the same operation is carried out as before.

In the progressive carrying out of the process in the several retorts, additional preservative is drawn from the source of supply through the pipe E, and added to the 10 residual amount of preservative carried from each retort to the next, to complete the amount required for the impregnation of the charge in said second retort.

It is obvious from the foregoing that the 15 maximum amount of preservative oil in use in carrying out my improved process, is the contents of one retort, plus the amount used in the preliminary drenching of the charge in another retort, and with the completion 20 of the treatment of each charge of ties, only an amount equal to that which has been absorbed in the impregnation of such charge is drawn from the source of oil supply, as contrasted with other methods in which the 25 entire amount drained from a retort has to be returned to the reservoir, and a new full amount drawn from such reservoir for the treatment of the next in the retort.

It is also obvious that the original charge 30 of compressed air is utilized by being transferred from retort to retort, no further supply or operation of the compressor being required, except to restore the maximum pressure in case of any leakage of air from the 35 system.

Consequently by means of my improved process carried out by the described apparatus manifest economies are secured in the 40 heating of the oil, in maintaining the working supply of compressed air, and in time consumed in the process, in that three charges of ties are simultaneously operated upon by one charge only of both oil and compressed air. Other minor economies 45 also in time and labor, are made possible by reason of the intercommunication of the elements of the apparatus in the cycle, and the interdependent operations or steps of the process.

50 Having thus described my invention, what I claim and desire to secure by Letters Patent is:

1. The method of impregnating wood with a liquid preservative, consisting in arranging the articles in groups in a three-fold cycle, then drenching the first group with the preservative under subatmospheric or atmospheric pressure and continuing the 55 drenching under superatmospheric pressure, then to submergence in the preservative under increasing hydraulic pressure only, and then to atmospheric or subatmospheric pressure only, the submerging action of the preservative causing superatmospheric pressure 60 upon the articles in the second group,

and the withdrawal of the submerging liquid from the first group causing the submergence of the second group and consequent superatmospheric pressure upon the third group, the performance of each operation 70 upon the third group causing successively prior operations upon a new first group.

2. The method of impregnating wood with a liquid preservative under atmospheric, superatmospheric, and hydraulic 75 pressures, successively, which consists in subjecting the articles to such treatment in a three-fold cycle, the coincident operations in the several cycles being different, the completion of the operation in each cycle initiating, and carrying through a like operation in the succeeding cycle.

3. The method of impregnating railway ties, or other porous articles, with a preservative liquid, which consists in manipulating successively similar groups of ties in a three-fold cycle, subjecting them to compressed air, and then to submergence in the preservative liquid with progressively increasing hydraulic pressure and subjecting 90 them to a vacuum by withdrawing the immersing preservative, the operation of immersing one group causing the subjection of the second to compressed air and the withdrawal of the liquid from the first group 95 causing submergence of the second and application of compressed air to the third, and like operations upon the third causing like operations upon a new substitute group for the first.

4. The method of impregnating railway ties and the like with a liquid preservative, which consists in first arranging such ties in successive groups in a three-fold cycle, then drenching the first group with preservative liquid at atmospheric or subatmospheric pressure, then continuing the drenching thereof with progressively increasing air pressure without submergence, then submerging it in the preservative and substituting progressively increasing hydraulic pressure for the air pressure, then withdrawing the preservative and subjecting it to atmospheric or subatmospheric pressure, the compressed air being transferred to the 105 second group by the submergence of the first, and the preservative withdrawn from the first group being transferred to submerge and impregnate the second, and to force the compressed air to the third, and so 110 on to substitutes of the several groups.

5. In connection with the treatment of railway ties and similar articles with a liquid preservative, whereby the article is first drenched with the preservative, then subjected to progressively increasing hydraulic pressure of the preservative only, then to the withdrawal of the excess preservative and reduction of pressure to or below atmospheric, the further process, which consists in 125 130

treating such articles in a three-fold cycle, each one in the cycle being subjected to the fluid discharge from the preceding one of the cycle.

- 5 6. In the treatment of railway ties with a liquid preservative, whereby they are first drenched with the preservative under subatmospheric or atmospheric pressure, then further drenched at increasing superatmospheric pressures, then subjected to progressively increasing hydraulic pressure of the preservative only, and then to atmospheric or subatmospheric air pressure only, the method which consists in arranging such ties 10 in similar groups in a three-fold cycle, and subjecting each group in the cycle successively to the fluid discharges from the preceding group.

7. The method of impregnating railway 20 ties with a liquid preservative in a three-fold cycle of air-tight retorts, which consists in first drenching the contents of the first retort with the preservative, then subjecting the same to progressively increasing 25 air pressure while continuing the drenching operation, then preliminarily drenching the contents of the second retort in the cycle with the preservative, then continuing the drenching operation under progressively increasing 30 air pressure by injecting the preservative by means of compressed air forced from the first retort by the submergence of the contents of the first retort with the preservative, and progressively increasing the 35 hydraulic pressure in the first retort, then withdrawing the surplus preservative from the first retort and conveying the same to the second to submerge its contents while the contents of the third retort are being 40 initially drenched with oil, and subjected to air pressure by the compressed air forced from the second retort by the submergence of its contents, then withdrawing the treated articles from the first retort and recharging 45 it with untreated articles, and then subjecting them to the fluid discharges from the third retort, in the manner described.

8. The method of impregnating railway 50 ties with a preservative liquid, consisting in arranging them in a three-fold cycle of retorts, then drenching those in the first retort of the cycle with the preservative, then continuing the drenching and subjecting them to progressively increasing air pressure without submergence, meanwhile 55 drenching those in the second retort with the preservative, then submerging the contents of the first retort in the preservative, and substituting progressively increasing 60 hydraulic pressure of the preservative for the air pressure, and meanwhile transferring the air from the first to the second retort to carry on the drenching operation, meanwhile drenching the contents of the 65 third retort with the preservative, then

transferring the preservative submerging the contents of the first retort to submerge those of the second retort, and reducing the pressure upon the contents of the first retort to or below atmospheric by withdrawing the 70 excess preservative therefrom and transferring to the second retort and thereby forcing the air from the second retort to the third to continue the drenching operation on the contents of the third retort, then substituting untreated ties for the treated ones in the first retort, then drenching them with the preservative, then in like manner transferring the compressed air from the third retort in the cycle to it, and continuing the 80 same series of steps as before, substituting untreated ties for the treated ones.

9. Apparatus for impregnating wood with a liquid preservative, comprising in combination, a cycle of three similar air-tight retorts each adapted to receive a charge of wood, interconnecting conduits placing said retorts operatively in a circulating series, sources of air pressure, of liquid preservative under pressure, and means for 90 producing subatmospheric pressure, all in communication with said conduits and adapted to so conduct the flow of the fluid as to subject the contents of said retorts successively to air pressure, then to liquid preservative under pressure and then to subatmospheric pressure, substantially as described.

10. In combination, a cycle of three similar air-tight retorts adapted each to receive a charge of wood, a source of supply of preservative liquid under pressure, a vacuum producing means, and interconnecting conduits whereby the contents of said retorts may be subjected successively to 100 drenching by the preservative liquid under atmospheric or subatmospheric pressure, then to further drenching under superatmospheric pressure, then to submergence in the preservative liquid and hydraulic pressure only, then to atmospheric or subatmospheric pressure only, then to the withdrawal of the submerging liquid and then to the subjecting of the said material to a vacuum, the fluids being conveyed from each retort 110 to the next in the cycle to subject its contents to like treatment.

11. Apparatus for impregnating wood, comprising three similar retorts adapted to be charged with the wood to be treated, 120 vacuum producing apparatus, an air compressor, a supply of preservative liquid, means for applying pressure to said liquid, a series of conduits interconnecting all said elements in a continuous circulating system 125 adapted to subject the material placed in said retorts successively in any desired order to atmospheric, subatmospheric, or superatmospheric pressure and to the pressure of said liquid, the coincident operations in 130

said retorts being different, and each being caused by the completing of the corresponding operation in the preceding retort.

12. In combination, a cycle of three similar retorts having valve-controlled interconnecting conduits, a source of preservative oil supply, a combination oil and vacuum pump having valve-controlled communication with said oil supply and with said retorts, a manifold oil container, and a compressed air pump having valve-controlled operative connections through said container with each of said retorts, substantially as set forth.
13. In combination, a cycle of three similar retorts, valve-controlled conduits interconnecting said retorts and permitting the discharge of the fluid contents of each into the next one of the cycle, a source of oil supply, an oil pump connected therewith and also with each of said retorts, valve-con-

trolled connections between said oil supply and each of said retorts and adapted to deliver into the selected retort oil for the initial drenching and for final submergence of 25 the contents, and for draining the oil contents from the retort and producing a vacuum therein, an air compressor, and a manifold oil container operatively interposed between said compressor and each of 30 said retorts.

14. The method of impregnating porous materials with a liquid which consists in carrying out the treatment upon similar groups of the materials in a three-fold cycle 35 and transferring the unused fluids and stored energy operating upon one group to the next in the cycle to perform a like operation thereon.

Signed at New York, county and State of 40 New York, this second day of Febr'y, 1916.

HENRY S. LOUD.
